UNITED STATES PATENT OFFICE

2,638,789

STEP-UP MECHANISM

Melvin J. Binks and Alphonse A. Samolis, Chicago, Ill., assignors to Republic Patent Corporation, Chicago, Ill.

Application April 25, 1951, Serial No. 222,912

7 Claims. (Cl. 74—158)

1

It is an object of the invention to provide such a mechanism which is simple in construction and economical in manufacture. Step-up mechanism which are presently used in marble pin ball game apparatuses are incapable of effecting more than one revolution of the contact wiper finger. This by reason of the fact that the ratchet wheel is limited in its rotation by a spring which serves to return the ratchet wheel to a starting position.

A principal object of our invention is to provide in a step-up mechanism a ratchet wheel which is not thus limited, with the end result that we are able to register by illumination a higher score than that registered by illumination in game apparatuses employing the present type of step-up mechanisms, that is, one limited in its rotation by its return spring.

A still further and equally important object of the invention is to provide a step-up mechanism of the class hereinafter described which will be simple and effective in use with the operating parts cooperating in a simple manner to facilitate their assembly in a single unitary structure.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is an elevational view of my improved step-up mechanism;

Fig. 2 is a top plan view of the same taken on line 2—2 of Fig. 1;

Fig. 3 is a sectional detail view taken substantially on line 3—3 of Fig. 2;

Fig. 4 is a fragmentary perspective view of the same;

Fig. 5 is a back view of the same taken substantially on line 5—5 of Fig. 2; and

Fig. 6 is a suggested circuit diagram illustrating one of the many uses of my step-up mechanism.

The several objects of the invention are accomplished by the preferred form of construction shown in the accompanying drawings. In these drawings a mounting plate is indicated at 10. By means of brackets 11 extending from the four corners of this plate 10, such plate is mounted to a stationary wall 12.

To the rear of the plate 10 and supported therefrom by a bracket 13 is a plate 14 of non-conductive material and having secured thereto in equal spaced relation with respect to each other contact heads 15 which are adapted to be connected

2

in circuit with incandescent lamps hereinafter referred to.

The plates 10 and 14 have formed therein aligned openings in which a shaft 16 is journaled. The inner end portion 17 of the shaft 16 carries a wiper blade 18, the outer end 19 of which is adapted to successively engage the contact heads 15. Fixed to the outer end 20 of the shaft is a bushing 21. This bushing 21 carries a ratchet wheel 22. A second ratchet wheel 23 is arranged in spaced confronting relation with respect to the ratchet wheel 22 and is secured in such spaced relation by means of bolts 24 projected through spacing sleeves 25.

As particularly noted in Fig. 4, the teeth of the ratchet wheel 23 extend in a direction opposite to that of the teeth of the ratchet wheel 22. It is apparent that the ratchet wheels 22 and 23 rotate together in the same direction of rotation.

Secured by suitable brackets 26 to the plate 10 are two electromagnetic coils 27 and 28, the coil 27 being a step-up coil and the coil 28 a reset coil.

The solenoid 29 of the step-up coil 27 is pivotally connected at 30 to a lever 31 in turn pivotally connected as at 32 to the plate 10. The upper end portion of the lever 31 is pivotally connected as at 33 to an arm 34. The outer end portion of this arm 34 provides a dog 35 adapted to engage successively the teeth of the ratchet wheel 22. Pivotally connected to this arm 34 as at 36 is the shank 37 of a closed cam frame 38, the top frame member of which is tapered downwardly and outwardly from the shank 37 as shown in Fig. 4.

Pivotally connected to the lever 31 as its point of pivotal connection with the plate 10 is an arm 39 providing a holding dog 40 which is adapted to engage the teeth of the wheel 22. A finger 41 is provided on a plate 42 and is adapted to be engaged by a finger 43 provided as an extension of the holding dog 40 to limit the pivotal movement of such dog by the action of a spring 44 having one end portion 45 connected to the arm 39 and an opposite end portion 46 connected to the plate 42. The outward movement of the solenoid 29 is limited by a head bearing adjustment screw 47.

The solenoid 48 of the coil 28 is pivotally connected as at 49 to a lever 50 in turn pivotally connected as at 51 to the plate 10. The outward movement of the solenoid 48 is limited by a head bearing adjustment screw 48'. The upper end portion of this lever 50 is pivotally connected as at 51' to an arm 52 providing a reset dog 53 extending substantially at right angles with respect

50
55

to the arm 52 and normally resting upon the lower bar 54 of the cam frame 38. Pivotally connected as at 55 to the arm 52 is the shank 56 of a cam frame 57 similar in construction to the cam frame 38 but having its top bar 58 extending downwardly away from the shank 56. The dog 35 extends through the frame 57 and normally rests on the lower bar 59 thereof. As seen in Fig. 4, the cam frames 38 and 57 are arranged in confronting relation with respect to each other. Projecting through these frames at a point adjacent the apex of each frame is a pin 61. This pin 61 is connected as at 62 to the plate 10.

Pivotally connected to the lever 50 at its point of pivotal connection 51 to the plate 10, is an arm 63 providing a dog 64 adapted to engage the teeth of the ratchet wheel 23. Like the dog 40, this dog 64 is limited in its pivotal movement toward the teeth by a stop finger 65 adapted to engage a blocking finger 66. The pivotal movement of the dog 64 into engagement with the teeth of the wheel 23 is under action of a spring 67 having one end portion 68 connected to the arm 63 and an opposite end portion 69 connected to a plate 10 formed as an integral part of the finger 65 and connected to the lever 50 as at 71.

The levers 34 and 50 each provide an upwardly extending portion 72 connected together by a spring 73 which normally retains the levers in the position shown in Fig. 1.

Our improved step-up mechanism may be used to control various electric circuits. However, such step-up mechanism has been especially designed by us for the use in a circuit of a pin ball game apparatus in which there are arranged a plurality of incandescent lamps 74 which, when illuminated, illuminate a score which has been attained by the player.

The contact heads 15 may represent different score values. The incandescent lamps 74 represent score values corresponding to the contact heads in circuit therewith. In this circuit diagram we have illustrated every ninth contact head as being connected in circuit with a step-up mechanism 76. This step-up mechanism is substantially similar to that shown in United States Patent No. 2,281,262, wherein there are disclosed among other things, a wiper finger 77, contact heads 78, a step-up coil 79 and a reset coil 80. The step-up coil 79 operates a step-up pawl 81 while the reset coil operates a reset arm 82 and a holding pawl 82'. The contacts 78 are connected in circuit with incandescent lamps 83 having score values corresponding to the value of the contact heads 78. For example, assuming that each contact head 15 has the value of "1," inasmuch as every ninth contact head of the contact heads 15 is connected in circuit with a contact head 78, the score value of the first lamp of the lamps 83 will be "10," the second "20," the third "30," and so on. The circuit illustrated in Fig. 6 is to show one of the many uses of our invention and it is to be understood that we are not to be limited to such circuit; also while we have shown but one row of contact heads 15 and one wiper finger 78, there may be several such rows concentrically arranged with respect to each other and each engaged by a wiper finger.

The operation of our improved step-up mechanism is as follows:

The wheels 22 and 23 are advanced step-by-step in a clockwise direction through the step-up dog 35. This is accomplished as follows:

When the switch 84 (which switch may represent a ball-actuated switch or the like) is closed,

the coil 27 will be energized and project the lever 31 so as to move the arm 34 to the left as viewed in Fig. 1. As this arm 34 is moved in such direction, the cam frame 38 moves therewith and, as the top bar thereof engages the pin 61, the cam frame 38 will be pivoted in an upward direction, disengaging the dog 53 from the adjacent tooth of the wheel 23. Simultaneous with this movement of the frame 38 the stop finger 41 having been moved upon pivotal movement of the lever 31 in an anti-clockwise direction from engagement with the finger 43, the dog 40 will be permitted to move into engagement with the adjacent tooth of the rear wheel 22, thus holding the wheels 22 and 23 against movement in an anti-clockwise direction. Pivotal movement of the lever 31 in a clockwise direction will bear the dog 35 against the adjacent tooth and rotate the wheels 22 and 23 in a clockwise direction. During this operation, the dog 64 has been held from engagement with the outer wheel 23 by the spring 27.

Each time the electromagnetic coil 27 is energized, the wheels 22 and 23 will be advanced step-by-step.

Each time the electromagnetic coil 28 is energized by the closing of a switch 84' (which switch may be a conventional coin slide switch which conditions the game apparatus for play), the ratchet wheels 22 and 23 will be rotated in an anti-clockwise direction. This is accomplished in the following manner: When the solenoid 29 is moved inwardly with respect to the coil 28, the lever 50 is pivoted in a clockwise direction. This permits the dog 64 to move into engagement with the outer wheel 23 to hold the ratchet wheels 22 and 23 against rotation in a clockwise direction. As the lever 50 projects in a clockwise direction, the cam frame 57 thereof pivots therewith and brings the top bar 58 thereof into engagement with the pin 61, pivoting the frame upwardly to bear the bottom bar of the frame 57 against the dog 35 to pivot the dog upwardly from engagement with the adjacent tooth of the wheel 22. At the same time, the dog 53 is moved back one tooth to engage the next tooth of the wheel 23. When the lever 50 is pivoted in a clockwise direction by the spring 73, the wheels 22 and 23 will be rotated one step in an anti-clockwise direction, equivalent to the distance between the tooth of the wheel 23. Each time the coil 28 is energized, the wheels 22 and 23 will be rotated in an anti-clockwise direction, as viewed in Fig. 1, one step equivalent to the distance between the teeth.

In the construction of our step-up mechanism we do not limit the rotation of the wheels 22 and 23 by any return spring. The wheels are therefore free to be rotated step-by-step through several revolutions. This is important because it permits the utilization of a larger number of contact heads, with the end result that a larger score may be registered by illumination than is ordinarily registered by the use of step-up mechanism now commonly in use.

While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come within the scope of the appended claims.

Having thus described our invention, what we

claim as new and desire to protect by Letters Patent is:

1. A step-up mechanism of the class described comprising a support, a shaft rotatably supported by said support, a disc bearing a plurality of contacts supported by said support, a wiper finger on one end of the shaft and adapted for successive engagement with the contacts of said disc, a first ratchet wheel on said shaft, a second ratchet wheel arranged in confronting spaced relation with respect to said first ratchet wheel, means for connecting said ratchet wheels in said spaced relation with respect to each other, the teeth of said first ratchet wheel extending in a direction opposite to that of the teeth of the second ratchet wheel, means for successively engaging the teeth of the first ratchet wheel to rotate said ratchet wheels in one direction, means for successively engaging the teeth of the second ratchet wheel for rotating said ratchet wheels in an opposite direction and means for holding one of said ratchet wheel rotating means while the other of said ratchet wheel rotating means is effective to rotate said ratchet wheels, said last-named means including cam frames extending from one end of each of said ratchet wheel rotating means and adapted to cam the ineffective ratchet wheel rotating means out of engagement with its respective ratchet wheel.

2. A step-up mechanism of the class described comprising a support, a shaft rotatably supported by said support, a disc bearing a plurality of contacts supported by said support, a wiper finger on one end of the shaft and adapted for successive engagement with the contacts of said disc, a first ratchet wheel on said shaft, a second ratchet wheel arranged in confronting spaced relation with respect to said first ratchet wheel, means for connecting said ratchet wheels in said spaced relation with respect to each other, the teeth of said first ratchet wheel extending in a direction opposite to that of the teeth of the second ratchet wheel, means for successively engaging the teeth of the first ratchet wheel to rotate said ratchet wheels in one direction, holding means for said first ratchet wheel when said first ratchet wheel is rotated in said one direction, means for successively engaging the teeth of the second ratchet wheel for rotating said ratchet wheels in an opposite direction, holding means for said second ratchet wheel when said second ratchet wheel is rotated in said direction opposite to said one direction, and means for holding one of said ratchet wheel rotating means while the other of said ratchet wheel rotating means is effective to rotate said ratchet wheels, said last-named means including cam frames extending from one end of each of said ratchet wheel rotating means and adapted to cam the ineffective ratchet wheel rotating means out of engagement with its respective ratchet wheel.

3. A step-up mechanism of the class described comprising a support, a shaft rotatably supported by said support, a disc bearing a plurality of contacts supported by said support, a wiper finger on one end of the shaft and adapted for successive engagement with the contacts of said disc, a first ratchet wheel on said shaft, a second ratchet wheel arranged in confronting spaced relation with respect to said first ratchet wheel, means for connecting said ratchet wheels in said spaced relation with respect to each other, the teeth of said first

ratchet wheel extending in a direction opposite to that of the teeth of the second ratchet wheel, electromagnetic means for successively engaging the teeth of the first ratchet wheel to rotate said ratchet wheels in one direction, electromagnetic means for successively engaging the teeth of the second ratchet wheel for rotating said ratchet wheels in an opposite direction and means for holding one of said ratchet wheel rotating means while the other of said ratchet wheel rotating means is effective to rotate said ratchet wheels, said last-named means including cam frames extending from one end of each of said ratchet wheel rotating means and adapted to cam the ineffective ratchet wheel rotating means out of engagement with its respective ratchet wheel.

4. A step-up mechanism of the class described comprising a support, a shaft rotatably supported by said support, a disc bearing a plurality of contacts supported by said support, a wiper finger on one end of the shaft and adapted for successive engagement with the contacts of said disc, a first ratchet wheel on said shaft, a second ratchet wheel arranged in confronting spaced relation with respect to said first ratchet wheel, means for connecting said ratchet wheels in said spaced relation with respect to each other, the teeth of said first ratchet wheel extending in a direction opposite to that of the teeth of the second ratchet wheel, electromagnetic means for successively engaging the teeth of the first ratchet wheel to rotate said ratchet wheels in one direction, holding means for said first ratchet wheel when said first ratchet wheel is rotated in said one direction, electromagnetic means for successively engaging the teeth of the second ratchet wheel for rotating said ratchet wheels in an opposite direction, holding means for said second ratchet wheel when said second ratchet wheel is rotated in said direction opposite to said one direction, and means for holding one of said ratchet wheel rotating means while the other of said ratchet wheel rotating means is effective to rotate said ratchet wheels, said last-named means including cam frames extending from one end of each of said ratchet wheel rotating means and adapted to cam the ineffective ratchet wheel rotating means out of engagement with its respective ratchet wheel.

5. A step-up mechanism of the class described comprising a support, a shaft rotatably supported by the support, a first ratchet wheel on said shaft, a second ratchet wheel arranged in confronting spaced relation with respect to said first ratchet wheel, means for connecting said ratchet wheels in said spaced relation with respect to each other, the teeth of said first ratchet wheel extending in a direction opposite to that of the teeth of the second ratchet wheel, means for successively engaging the teeth of said first ratchet wheel to rotate said ratchet wheel in one direction, means for successively engaging the teeth of the second ratchet wheel for rotating said ratchet wheels in an opposite direction, and means for holding one of said ratchet wheel rotating means while the other of said ratchet wheel rotating means is effective to rotate said ratchet wheels, said last-named means including cam frames extending from one end of each of said ratchet wheel rotating means and adapted to cam the ineffective ratchet wheel rotating means out of engagement with its respective ratchet wheel.

6. A step-up mechanism of the class described

comprising a support, a shaft rotatably supported by the support, a first ratchet wheel on said shaft, a second ratchet wheel arranged in confronting spaced relation with respect to said first ratchet wheel, means for connecting said ratchet wheels in said spaced relation with respect to each other, the teeth of said first ratchet wheel extending in a direction opposite to that of the teeth of the second ratchet wheel, electromagnetic means for successively engaging the teeth of said first ratchet wheel to rotate said ratchet wheel in one direction, electromagnetic means for successively engaging the teeth of the second ratchet wheel for rotating said ratchet wheels in an opposite direction, and means for holding one of said ratchet wheel rotating means while the other of said ratchet wheel rotating means is effective to rotate said ratchet wheels, said last named means including cam frames extending from one end of each of said ratchet wheel rotating means and adapted to cam the ineffective ratchet wheel rotating means out of engagement with its respective ratchet wheel.

7. A step-up mechanism of the class described comprising a support, a shaft rotatably supported by the support, a first ratchet wheel on said shaft, a second ratchet wheel arranged in confronting spaced relation with respect to said first ratchet wheel, means for connecting said ratchet wheels in said spaced relation with respect to each other, the teeth of said first ratchet wheel extending in a direction opposite

5
